UNITED STATES PATENT OFFICE.

JOHN J. CONLIN, OF BRADDOCK, PENNSYLVANIA.

WATER SEAL.

Application filed May 4, 1923. Serial No. 636,667.

This invention relates to water seals and more particularly to a water seal container, which although not limited thereto, is primarily adapted for use on the washers of a sintering apparatus.

One object of this invention is to provide a water seal container which may be readily cleaned when clogged or stopped with sludge or other foreign matter.

Another object is to provide such a container with an overflow outlet adapted to be normally closed and which will automatically open when the quantity of water in the container is increased beyond a predetermined amount due to clogging of the normal outlet, thereby permitting the escape of the excess water and also warning the operator that the container is clogged.

A further object is to provide a water seal having the novel construction, design and combination of parts hereinafter described and illustrated in the accompanying drawings.

In the drawings, Figure 1 is a side elevation of a sintering plant embodying the novel features of my invention.

Figure 2 is a end elevation of the apparatus of Figure 1.

Figure 3 is an enlarged sectional elevation through one of the gas washers.

Figure 4 is an enlarged side elevation and Figure 5 is an enlarged end elevation of the water seal mounted on the lower end of the gas washer sludge or drain pipe.

Figure 6 is an enlarged sectional elevation through the water seal of Figures 4 and 5.

Referring more particularly to the drawings, the numeral 2 designates the sintering pan which is arranged to tilt or rock about a horizontal axis, opposite ends of this pan being provided with hollow trunnions 3-3, by which the pan is rotatably mounted in suitable trunnion bearings.

The pan 2 has a bottom 5, sides 6, 6 and integrally formed ends 7, the hollow trunnions 3-3 opening into the pan through the end walls of the pan. At an intermediate point in the height of the side walls of the pan is a series of perforated grate bars 8, these bars being held in position by transverse perforated supports 8a.

Girders 9, which extend longitudinally along each side of the pan 2, carry flanged track rails 9a forming a track for charging cars and gas igniters.

The outer ends of the hollow trunnions 3 are connected to one end of pipes 10-10, which form conduits for leading the gaseous products of combustion from beneath the grate bars 8 in the pan 2 into the gas washers 11-11 to which the other ends of the pipes 10-10 are connected.

Pipes 12-12 which are connected to the lower ends of the washers 11-11 form conduits for leading the cleaned and cooled gaseous products of combustion from the gas washers to the inlet on the exhaust blower or fan 13, to which the lower end of the pipes 12-12 are connected.

The exhaust fan or blower 13 is connected by a branch pipe 15 to the lower end of a stack 16 adapted to carry off the gaseous products of combustion.

The washers 11-11 comprise an outer casing or wall 17 having a removable top or head 18 and a removable bottom 19. The top 18 is provided with a centrally arranged inlet 20, which extends downwardly within the washer for an appreciable distance. The upper end of the inlet 20 is provided with a flange 21, connected to a flange on the end of the pipes 10-10, leading from the ends of the sintering pan 2.

The bottom 19 is provided with an inclined wall 24 and has a centrally arranged outlet conduit 26 which extends upwardly within the washer for an appreciable distance. The outlet conduit 26 has a plurality of slots 27 at its upper end which form gas inlets. The conduit 26 is provided on its lower end with a flange 30 which connects with the flanged upper end of the conduits or pipes 12.

Water is sprayed into the stream of highly heated gaseous fluid or burned gases flowing through the gas washing chamber by a series of radial nozzles 31, these nozzles being arranged in the conduit pipes 10-10 above the upper ends of the washers 11, and the baffles 32, 33 and 34 within the washer cause the said gases and water to travel through a tortuous path, and compels the gases to pass and repass through the falling rain of water in the travel thereof through the washer.

The baffle 32 comprises a vertical side 35 and an integral bottom 36, the bottom being conical and being inclined toward the center of this baffle. (See Figure 3.) A small centrally located outlet opening 37 in the bottom 36 has a depending tubular portion

38, and a series of ribs 39 are formed on the inner surface of the side and bottom of this wall, and converge toward the outlet opening 37 in the tubular extension 38. A 5 plurality of narrow radial slots 40 are provided in the bottom 36 through which a portion of the water and sludge falls.

The side wall 35 of the baffle 32 is spaced from the inlet conduit 26, but extends above 10 the lower edge of this conduit.

The third baffle 34, which is supported on the upper end of the outlet conduit 26, comprises a bottom wall 41 which inclines to one side thereof, and the central portion of 15 the bottom 41 is projected upward in the form of a cone, its apex or peak 42 being located slightly below the lower edge of the depending tubular extension 38 on the baffle 32. An integral rim portion 43 extends 20 around the major portion of the bottom 41, being cut away for a space along the lowermost edge of said bottom 41.

The second or intermediate baffle 33 is supported on the lower baffle 34 and comprises a tubular body 44 having a flange 45 which extends outwardly and downwardly from the upper edge of the body 44. This flange is provided on its upper surface with a plurality of radial ribs 46, and the flange 30 45 is only of sufficient diameter to leave a very small annular opening or space between the edge of the flange and adjoining side wall of the washer.

Suitable openings or manholes are 35 provided in the side walls of the washer, these openings being closed by covers or heads 48 which, when removed, permit access to the interior of the washer in making repairs and in cleaning the washer.

40 A sludge pipe or drain 49 is connected to an outlet at the lowest point on the bottom of the washer. This pipe extends downwardly on an angle so that its lower end is substantially in alignment with the exhaust 45 fan 13.

It is essential that the pipes 49 be provided with a water seal to prevent the inlet of air therethrough. In the present embodiment of my invention I have shown a 50 water seal 50 having an inlet 51 at its upper end connected to the pipes 49 and a reduced outlet 52 at its lower end. The outlet is of materially less diameter than the inlet and is of such a size that it will discharge about the same or less water in a 55 given time than enters the washers 11. That is, the contracted outlet 52 must hold back a sufficient amount of water in the body of the seal member 50 to form a true water seal. It will, therefore, be apparent that 60 the outlet 52 must always be of such a size that it will never discharge more water in a given time than enters the washers 11.

65 The body of the seal 50 is supported on suitable brackets 53 and is provided with an

overflow outlet 54 provided with a spout or lip 55 and an inclined hinged closure 56. The closure 56 is provided with a rubber lining or pad 57 adapted to form a tight joint with the seat 58 around the outlet 54. 70

The outlet 52 and overflow 54 are adapted to discharge into a suitable trough 59 leading to a suitable sump 60.

In operation the sludge and water from the washers 11 will be held back in the 75 seal 50 in sufficient quantity to form a liquid seal and prevent the inflow of air through the outlet 52, and if for any reason the sludge or other foreign matter should clog or partially close the outlet 52 80 so that the rate of discharge was less than necessary to carry off the water and sludge from the washer 11 the water will rise in the seal 50 until it reaches the overflow outlet 54 when it will open the cover or 85 closure 56 by its own weight and be discharged therethrough.

The discharge of the water and sludge through the overflow outlet 54 will serve 90 as a warning to the operators of the plant that the outlet 52 is clogged and they may then readily open the outlet by forcing a bar or similar tool therein. The operation of opening the outlet 52 may be readily accomplished without stopping the operation 95 of the plant and without dismantling any of the apparatus, and this is quite an improvement over any water seal equipment heretofore used. The inclined mounting of the closure 56 and the partial vacuum maintained in the system by the fan 13 combine 100 to normally maintain the closure 56 in closed position.

While I have shown and described only 105 one specific embodiment of my invention it will be understood that I do not wish to be limited thereto, since various modifications may be made without departing from the scope of my invention as defined in the 110 appended claims.

I claim:—

1. The combination with a conduit for conveying liquid, of a liquid seal container secured to the lower end of said conduit, 115 said seal container having a contracted outlet at its lower end and an overflow outlet in its side wall at a point above said contracted outlet, said contracted outlet being of such size as to normally hold back a quantity of liquid in said container to form a liquid seal, and said overflow outlet being provided with a hinged closure adapted to normally form a tight joint and to be automatically opened by the pressure of the liquid in said container when its quantity is increased beyond a predetermined amount. 120

2. The combination with a sludge and drain pipe leading from a gas washer and discharging into a receiving drain, of a 125

liquid seal container secured to the lower end of said pipe and having a contracted outlet at its lower end and an overflow outlet in its side wall at a point above said outlet, said liquid seal container being positioned above said receiving drain so as to permit free access to said contracted outlet for cleaning, said contracted outlet being of such size as to normally hold back 10 a quantity of liquid in said container to form a liquid seal, and said overflow outlet being provided with a hinged closure adapted to normally form a tight joint and to be automatically opened by the pressure 15 of the liquid in said container when its quantity is increased beyond a predetermined amount.

3. A liquid seal container for sludge and drain pipes of gas washers and the like,

comprising a hollow container having an inlet opening of approximately the same size as the pipe to which it is connected and a contracted outlet at its lower end, and being further provided with an overflow outlet in its side wall at a point above 25 said contracted outlet, said contracted outlet being of such size as to normally hold back a quantity of liquid in said container to form a liquid seal, and a hinged closure for said overflow outlet adapted to normally 30 close said overflow outlet and to be automatically opened by the pressure of the liquid in said container when its quantity is increased beyond a predetermined amount.

In testimony whereof I have hereunto set 35 my hand.

JOHN J. CONLIN.
